Primary Examiner—Alan P. Douglas*Assistant Examiner*—M. N. Pandozzi*Attorney, Agent, or Firm*—Cornell D. M. Judge Cornish**[57] CLAIM**

The ornamental design for cup with pompon and pompon cover, as shown as described.

DESCRIPTION

FIG. 1 is an exploded top perspective view of a cup with pompon and pompon cover showing my new design;

FIG. 2 is a bottom plan view thereof;

FIG. 3 is a side elevational view thereof with the pompon in its stored position;

FIG. 4 is a partial side elevational view broken away for ease of illustration;

FIG. 5 is a partial rear elevational view thereof, where the upper portion is broken away for ease of illustration; and,

FIG. 6 is a top plan view thereof.

FIG. 3

FIG. 4

FIG. 5

FIG. 6

FIG. 2
